SLIDE FASTENER STOP ATTACHING
MACHINE

Lorenz F. Muther, Newton Center, Mass.

Application July 25, 1940, Serial No. 347,439

5 Claims. (Cl. 153—1)

This invention relates to a machine for attaching slide fastener top and bottom stops.

The primary object of this invention is to provide a novel machine for automatically feeding and clenching slide fastener top and/or bottom stops in proper position upon the slide fastener tapes.

Further objects are the provision of a machine having a device to receive and carry a top and/or bottom stop from the feeding means to the clenching means, a device for automatically positioning the stop in a predetermined position upon said carrying device, and a device for holding the stop in predetermined position upon the carrying device until the stop has been clenched.

Other objects will be apparent from a consideration of the accompanying drawings in which one embodiment of the invention is illustrated. In the drawings:

Fig. 1 is a side elevational view of the machine with parts broken away;

Fig. 2 is a section on the lines 2—2 of Fig. 1;

Fig. 3 is a view similar to Fig. 2 but with the stop carrying member retracted to a position to receive a stop from the end of the raceway;

Fig. 4 is an enlarged end elevational view looking from left to right at Fig. 1;

Fig. 5 is a section on the lines 5—5 of Fig. 4; and

Fig. 6 is a perspective view of a completed slide fastener.

A slide fastener (Fig. 6) consists of two tapes 8 to which the outwardly extending ends of the interlocking members 9 are clamped. A bottom stop 10 is firmly secured to the tapes in such a position that it bridges the opening between them, thereby limiting the downward movement of the slide 12. This bottom stop consists of an upper and a lower member which are parallel and of a narrow strip of metal which connects the upper and lower members. The tapes are gripped between the opposite ends of the parallel members and the connecting band of metal extends between the adjacent edges of the tapes.

A top stop 11 is provided adjacent the upper end of each row of interlocking members 9. The top stop consists of a strip of metal which is folded intermediate its ends to provide an upper member and a lower member which are spaced apart. The top stop is affixed in position so that the edge of the tape extends between the upper and lower members and is ad-

jacent the line of fold. The top stops serve to limit the upward movement of the slider 12.

The machine of this invention may be used to clench or affix either the bottom stops or the stops to the tapes so that they are clenched by the machine in the respective positions shown in Fig. 6 thereby to complete the slide fastener assembly. Although the drawings illustrate only bottom stops in position in the machine, it will be apparent that top stops may be fed and clenched by the same machine.

The machine comprises a frame 20 which may be supported upon any convenient bench or table. A transverse horizontal shaft 21 is mounted for rotation in bearings in the frame. A cam 22 is secured to the shaft 21 adjacent one end to rotate with the shaft. A lever arm 23 is mounted for rotation about the horizontal shaft 24 and the ends of said shaft are supported by suitable bearings which are supported by the frame of the machine. A follower roll 26 is pivotally secured adjacent one end of the lever arm and is held in engagement with the edge face of the cam 22 by the coil spring 27. A link 28 has one end pivotally secured to the other end of the lever arm by a cotter pin 29. The lower end of said link is pivotally secured to the upper end of the vertical shaft 31 by the cotter pin 30.

30 The shaft 31 is mounted for vertical movement in a vertical chamber provided in the arm 32 which is integral with the frame of the machine.

35 The lower end of the shaft 31 is normally located directly above the surface of the adjacent end of the finger 34.

Thus, looking at Fig. 1, the lower end of the shaft 31 is normally in the elevated position there illustrated, but when the shaft 21 is rotated, the projection on the cam 22 elevates the adjacent end of the lever arm 23, lowers the other end of said arm, and forces the shaft 31 to move downwardly so that its lower end strikes the end of the finger 34 and compresses the top and bottom sides of the bottom stop 10 into engagement with the tapes of the slide fastener while the tapes are held in the position shown in Fig. 2. When the cam 22 releases its pressure against the follower roll 26, the spring 27 again elevates the shaft 31 to the position of Fig. 1.

Each bottom stop is carried from the lower end of the raceway 35 to the clenching position shown in Fig. 1 by a horizontally slideable member consisting of the plate 36 and the member

37, which is integral with the plate 36 and extends longitudinally from the upper surface thereof (Figs. 1 and 4). These slideable members 36 and 37 are slideable horizontally in a horizontal channel, the sides and bottom of which are formed by the frame of the machine and the tops of which are secured to the frame by screws 39 (Figs. 4 and 5). The space between the adjacent longitudinal edges of the plates 38 is slightly greater than the width of the upstanding member 37 which in turn is slightly wider than a bottom stop. Thus a bottom stop located on the surface of the plate 36 with its edge resting against the end of the member 37 (as shown in Fig. 3) is free to be advanced by movement of the plates 36, 37 to the position shown in Figs. 1 and 2 without frictionally engaging the edge of the plates 38.

The slide 36, 37 is retracted from the position shown in Figs. 1 and 2 to the position shown in Fig. 3 and again returned to the clenching position of Figs. 1 and 2 by the cam 40, follower roll 41, arm 42 and link 43. The cam 40 is secured to the horizontal shaft 21 and is rotatable therewith. The follower roll 41 is pivotally secured to the upper end of the arm 42 which is mounted for rotation about a horizontal shaft 45. This horizontal shaft 45 is rotatably supported in bearings supported by the frame. The lower end of the arm 42 is pivotally secured to one end of the link 43 and the other end of said link is pivotally secured by a pin 92 to the lug 46 which is integral with the slide member 37. The tension spring 110 has one end secured to the frame portion 32 and the other end secured to the arm 42. This spring 110 keeps the follower roll 41 in contact with the edge of the cam 40.

When the cam 40 is rotated clockwise (looking at Fig. 1), it causes the lower end of the arm 42 to move from left to right (looking at Fig. 1), thereby retracting the slide 36, 37 from the position of Figs. 1 and 2 to the position of Fig. 3, where the end of the member 37 has passed the line of bottom stops in the raceway so that it does not obstruct the outward movement of the lowermost bottom stop from the end of the raceway to the surface of the member 36. As the cam 40 continues its rotation, the slide 36, 37 is returned to the position of Figs. 1 and 2 by the spring 110.

The finger 34 is pivotally mounted intermediate its ends upon the lug 47 which is integral with the slide member 37. A compression spring 48 has its upper end abutting the bottom surface of one end of the finger 34 and tends to elevate said end of the finger and to force the opposite end of the finger downwardly into engagement with the upper surface of a bottom stop located upon the surface of the slide 36, as shown in Fig. 1. Thus the finger 34 functions to hold the bottom stop in a predetermined position upon the surface of the slide member 36.

A horizontal pin 50 is secured to the side of the finger 34 and a lug 51 having a beveled end surface is secured to one of the plates 38 (Figs. 2 to 5 inclusive). When the slide 36, 37 is moved to the fully retracted position shown in Fig. 3, the pin 50 rides upwardly along the beveled end surface of the lug 51, thereby moving the free end of the finger 34, to which the pin is attached, upwardly and lowering the other end of the finger against the pressure of the spring 48. This elevation of the free end of the finger raises its lower surface so that it does not contact the upper surface of the bottom stop when the bottom stop is forced from the end of the raceway outwardly upon the

surface of the plate 36. As soon as the slide 36, 37 begins its sliding movement back toward the shaft 31, the pin 50 leaves the beveled surface of the lug 51 and the spring 48 forces the free end of the finger 34 downwardly against the upper surface of the bottom stop. The finger remains in this position until the slide 36, 37 is again returned to the retracted position of Fig. 3.

The finger 54 is located in a space 57 (Fig. 1) 10 which is provided between one of the plates 38 and a depressed surface of the frame 20. The finger is mounted for reciprocation about the vertical pin 55 as an axis. The spring 56 tends to cause the finger to move in a clockwise direction (looking at Fig. 2) from the position shown in Fig. 2 to the position shown in Fig. 3. The thickness of the inner end of the finger is such that it 15 will loosely fit between the top and bottom sides of a bottom stop when the finger is rotated to the position shown in Fig. 3. When the slide 36, 37 is retracted to the position of Fig. 3, the finger 54 extends transversely across the space between the plates 38 and is spaced slightly above the surface of the slide member 36 and slightly away from the 20 end of the slide member 37. In this position of the finger 54 the lowermost bottom stop may be forced from the end of the raceway 35 upon the surface of the slide member 36 so that the top and bottom sides of the bottom stop straddle the 25 end of the finger 54 and one edge of the bottom stop lies between the edge of the finger 54 and the end of the member 37, as shown in Fig. 3. As the slide member 36, 37 advances toward the shaft 31, the finger 54 engages the top surface of the bottom stop and the finger 54 is rotated in a counterclockwise direction (looking at Fig. 3) by the 30 pressure of the end of the slide member 37 as it advances. As the slide 36, 37 continues to advance, the finger 54 is rotated to the position shown in Fig. 2 and it remains in that position until the end of the slide member 37 is returned again toward the end of the raceway and advances past the end of the finger. The spring 56 then causes the finger 54 to rotate clockwise to the 35 position of Fig. 3 where it is ready to guide another bottom stop into proper position upon the surface of the slide member 36.

The raceway 35 consists of a backing plate 60 (Figs. 4 and 5) and three plates 61, 62 and 63 40 which are secured thereto and which extend from the lower end of the raceway to the hopper wall 64 (Fig. 1); throughout their length the plates 61, 62 and 63 are in the relative positions shown in Fig. 5 so that a bottom stop may slide downwardly from the hopper along the inner edge of the plate 63 and can leave the raceway only by being forced from the lower end of the plate 63 which is slightly above the surface of the slide member 36 when said slide member is in the position of Fig. 3.

The hopper wall 64 is secured to the backing plate 60 and extends perpendicularly from its surface. Where the upper ends of the plates 61, 62 and 63 abut the hopper wall, a transverse opening is provided in the wall, which opening is of the proper shape and location to permit a bottom stop to pass therethrough into the raceway only end foremost so that the bottom stop must straddle the edge of the plate 63 and slide thereon in proper position to the lower end of the raceway.

The backing plate 60 also forms the bottom of the hopper and a removable cover (not shown) is secured to the end of the hopper wall 64 so that the supply of bottom stops in the hopper may be replenished from time to time. A brush

66 is secured to one end of the shaft 65. The shaft and brush are rotated forward and backward through an angle of about 60° so that the brush agitates the bottom stops in the hopper, thereby causing them to pass through the hopper wall opening into the upper end of the raceway.

The shaft 65 is rotated forward and backward by a crank 120, link 67, arm 68, arm 69, link 10, and wheel 71. The crank 120 has one end secured to the shaft 65 and the other end pivotally secured to one end of the link 67. The other end of the link 67 is pivotally secured to the upper end of the arm 68. The other end of the arm 68 is secured to one end of the shaft 72 which is supported for rotation in bearings. One end of the arm 69 is secured to the other end of the shaft 72 and the other end of the arm 69 is pivotally secured to the upper end of the link 70. The lower end of the link 70 is pivotally secured by a bolt 73 to the wheel 71 which is directly below the arm 69. The wheel 71 is secured to the horizontal shaft 74 which extends across the machine and is supported for rotation in suitable bearings. A wheel 75 is secured to the other end of the shaft 74. The wheel 76 is mounted for free rotation about the periphery of the shaft 21 and this wheel is continuously rotated about said shaft by a belt (not shown) connected with the drive shaft of an electric motor (not shown). The belt 78 connects the wheel 76 with the wheel 75 so that the latter wheel is continuously rotated by the former wheel.

Rotation of the wheel 75 causes rotation of the shaft 74 and of the wheel 71. Rotation of the wheel 71 causes alternate raising and lowering of the link 10 and of the attached end of the arm 69 which causes to and fro rotation of the arm 68 and longitudinal reciprocation of the link 67. Reciprocation of the link 67 causes to and fro movement of the crank 120 which causes forward and backward rotation of the shaft 65 and the brush 66.

The bottom stops slide to the lower end of the raceway by gravity but they are forced from the end of the raceway to the surface of the slide 36 by the outstanding portion 83 of the horizontal finger 80 (Figs. 4 and 5). The finger 80 is pivotally secured intermediate its ends between a pair of lugs 81 which are secured to a horizontal plate 82. The plate 82 is mounted in an undercut channel so that the plate is slidable horizontally toward and away from the lower end of the raceway.

The inner end of the finger 80 is formed with an outstanding portion 83 which is of reduced width so that its end will enter the space between the adjacent edges of the raceway plates 61 and 62, thereby to engage the edge of a bottom stop. A set screw 84 passes through the finger 80 and its lower end engages the surface of the plate 82, thereby forcing the other end of the finger downwardly against the pressure of the compression spring 85.

The horizontal arm 86 is mounted for rotation about the shaft of the bolt 87. One end of this arm is provided with a slot 88. The pin 89 is secured to the plate 82 and it extends transversely through the slot 88. An arm 90 is mounted for rotation about the shaft of the bolt 87. A vertical pin 91 is secured to the arm 90 adjacent one of its ends. A tension spring 94 has one end secured to the frame 75

to the arm 86. A tension spring 95 has one end secured to the arm 86 and the other end secured to the arm 90. The spring 95 is fully collapsed in the position of Figs. 2 and 5 and is extended in the position of Fig. 3. The spring 95 is stronger than the spring 94 so that when the arm 90 is rotated from the position of Fig. 2 to the position of Fig. 3, the spring 95 causes the arm 86 to rotate in the same direction.

10 The end of the pin 92 engages the pin 91 when the slide 36, 37 is moved from the position of Fig. 2 to the position of Fig. 3, thereby moving the link 90 in a counterclockwise direction about the bolt 87 (looking at Fig. 2). This causes the arm 86 to rotate about the bolt 87 in the same direction and the engagement between the slot 88 and the pin 89 causes the slide 82 to move from left to right (looking at Fig. 5) to a position in which the end of the projection 83 enters the raceway, engages the edge of a bottom stop, and thereby forces the lowermost bottom stop out from the end of the raceway upon the surface of the plate 36 and straddling the end of the finger 54 (see Fig. 3). When the cam 40 moves the slide 36, 37 from the position of Fig. 3 to the position of Fig. 2, the pin 92 is moved away from engagement with the pin 91 and the spring 94 returns the arms 90 and 86 to the position of Fig. 5, and such movement of the arm 86 causes the slide 82 also to return to the position shown in Figs. 4 and 5.

15 A foot pedal (not shown) is connected to the lower end of the rod 97 (Fig. 1) and the upper end of the rod 97 is connected to a clutch mechanism 98. When the foot pedal is depressed the clutch mechanism causes the shaft 21 to be rotated by the drive wheel 76.

20 When the foot pedal is elevated, the machine is in the position shown in Figs. 1, 2 and 5 so that a bottom stop is presented beneath the end of the shaft 31. The operator then places the slide fastener tapes between the upper and lower members of the bottom stop in the position shown in Fig. 2 and depresses the foot pedal which 25 causes rotation of the shaft 21. This causes the shaft 31 to be moved rapidly downwardly and its lower end strikes the upper surface of the finger 34 so that the parallel upper and lower sides of the bottom stop are moved toward each other 30 and the bottom stop is thereby clenched upon the tape to the completed position shown in Fig. 6.

35 The cam 40 then moves the slide 36, 37 to the retracted position shown in Fig. 3. During the latter part of this movement the spring 56 rotates the finger 54 to the position shown in Fig. 3 and the pin 50 engages the beveled top of the lug 51 thereby raising the end of the finger 34 so that it does not obstruct the end of the raceway. During the last part of this retracting movement of the slide 36, 37 the pin 92 engages the pin 91 and causes the end of the member 83 to be moved from the position shown in Fig. 4 into the raceway (see Fig. 3), thereby forcing the lowermost bottom stop out from the end of the raceway upon the surface of the plate 36 and straddling the finger 54. When the cam 40 has been further rotated and the spring 110 starts to return the slide 36, 37 toward the position of Figs. 1, 2, 4 and 5, the finger 34 immediately engages the top of the bottom stop, the finger 54 is then rotated to the position of Fig. 2, and the slide 36, 37 returns to the position of Figs. 1, 2, 4 and 5 with a fresh bottom stop in position to be clenched.

Upon each depression of the foot pedal the machine automatically repeats the above-described movements to clench the bottom stop which is in position beneath the shaft 31 and to receive a fresh bottom stop and return it to clenching position.

In use of the machine for affixing top stops instead of bottom stops, the only difference in operation is in the placing of the fastener tapes by the operator. In that case the edge of one tape is placed against the fold between the upper and lower member of the bottom stop and it is necessary to clench one bottom stop upon one tape and then to clench the next bottom stop upon the edge of the other tape.

I claim:

1. In a slide fastener stop-attaching machine having a raceway for feeding stops and stop-clenching means for securing the stops to stringers, a slidable member movable in a fixed path from a position adjacent to the end of said raceway toward and away from the stop-clenching means, said slidable member having a portion for receiving a stop from the end of the raceway, a positioning finger extending across the stop-receiving portion so as to engage a stop delivered from the end of the raceway and hold said stop on the stop-receiving portion, said finger being constructed and arranged to move from stop-holding position to a position clear of said fixed path in response to movement of said slidable member toward said stop-clenching means, and means for moving said slidable member from stop-receiving position to a position wherein the stop-receiving portion is adjacent to the stop-clenching means.

2. In a slide fastener stop-attaching machine having a raceway for feeding stops and stop-clenching means for securing the stops to stringers, a slidable member movable in a fixed path from a position adjacent to the end of said raceway toward and away from the stop-clenching means, said slidable member having a portion for receiving a stop from the end of the raceway, means for effecting delivery of a stop from said raceway to the stop-receiving portion of said slidable member, a stop-holding finger pivotally mounted upon said slidable member so as to engage and yieldingly hold a stop delivered to said stop-holding portion, means for moving said slidable member and stop-holding finger to a position in which the stop-engaging portion of the finger is adjacent to the stop-clenching means, and means for causing the stop-clenching means to strike said finger, thereby forcing the sides of the stop toward each other to clenched position while the stop is supported on said slidable member.

3. In a slide fastener stop-attaching machine having a raceway for feeding stops and stop-clenching means for securing the stops to stringers, a slidable member movable in a fixed path from a position adjacent to the end of said raceway toward and away from the stop-clenching means, said slidable member having a portion

for receiving a stop from the end of the raceway, a positioning finger extending across the stop-receiving portion so as to engage a stop delivered from the end of the raceway and position said stop on the stop-receiving portion, said finger being constructed and arranged to move from stop-holding position to a position clear of said fixed path in response to movement of said slidable member toward said stop-clenching means, a stop-holding finger pivotally mounted upon said slidable member so as to engage and yieldingly hold a stop positioned on said stop-holding portion, means for moving said slidable member and stop-holding finger to a position in which the stop-engaging portion of the finger is adjacent to the stop-clenching means, and means for causing the stop-clenching means to strike said stop-holding finger, thereby forcing the sides of the stop toward each other to clenched position while the stop is supported on said slidable member.

5 10 15 20 25 30 35 40 45 50 55 60

for receiving a stop from the end of the raceway, a positioning finger extending across the stop-receiving portion so as to engage a stop delivered from the end of the raceway and position said stop on the stop-receiving portion, said finger being constructed and arranged to move from stop-holding position to a position clear of said fixed path in response to movement of said slidable member toward said stop-clenching means, a stop-holding finger pivotally mounted upon said slidable member so as to engage and yieldingly hold a stop positioned on said stop-holding portion, means for moving said slidable member and stop-holding finger to a position in which the stop-engaging portion of the finger is adjacent to the stop-clenching means, and means for causing the stop-clenching means to strike said stop-holding finger, thereby forcing the sides of the stop toward each other to clenched position while the stop is supported on said slidable member.

4. In a slide fastener stop-attaching machine having a raceway for feeding stops and stop-clenching means for securing the stops to stringers, a slidable member movable in a fixed path from a position adjacent to the end of said raceway toward and away from the stop-clenching means, said slidable member having a portion for receiving a stop from the end of the raceway, a stop-feeding finger constructed and arranged so as to engage a stop positioned in the raceway and thereafter to force the stop located at the end of the raceway outwardly from the raceway to the stop-receiving portion of said slidable member, and means for moving said slidable member from stop-receiving position to a position wherein the stop-receiving portion is adjacent to the stop-clenching means.

5 10 15 20 25 30 35 40 45 50 55 60

5. In a slide fastener stop-attaching machine having a raceway for feeding stops and stop-clenching means for securing the stops to stringers, a slidable member movable in a fixed path from a position adjacent to the end of said raceway toward and away from the stop-clenching means, said slidable member having a portion for receiving a stop from the end of the raceway, a stop-feeding finger constructed and arranged to engage a stop positioned in the raceway and thereafter to force the stop outwardly from the raceway to the stop-receiving portion of said slidable member, a positioning finger extending across the stop-receiving portion so as to engage the stop delivered by said feeding finger and position it in a predetermined position on said stop-receiving portion, said positioning finger being constructed and arranged to move from the aforesaid operative position to a position clear of said fixed path in response to movement of said slidable member toward said stop-clenching means, and means for moving said slidable member from stop-receiving position to a position wherein the stop-receiving portion is adjacent to the stop-clenching means.
